Primary Examiner—T. Chase Nelson*(74) Attorney, Agent, or Firm*—Michael J. Striker(57) **CLAIM**

The ornamental design for a hand held drill, as shown and described.

DESCRIPTION

FIG. 1 is a perspective view of a first embodiment of a hand held drill showing my new design;
FIG. 2 is a side view thereof;
FIG. 3 is the opposite side view thereof;
FIG. 4 is a front view thereof;
FIG. 5 is a rear view thereof;
FIG. 6 is a top view thereof; and
FIG. 7 is a bottom view thereof.
FIG. 8 is a perspective view of a second embodiment of a hand held drill showing my new design;
FIG. 9 is a side view thereof;
FIG. 10 is the opposite side view thereof;
FIG. 11 is a front view thereof;
FIG. 12 is a rear view thereof;
FIG. 13 is a top view thereof; and
FIG. 14 is a bottom view thereof.
FIG. 15 is a perspective view of a third embodiment of a hand held drill showing my new design;
FIG. 16 is a side view thereof;
FIG. 17 is the opposite side view thereof;
FIG. 18 is a front view thereof;
FIG. 19 is a rear view thereof;
FIG. 20 is a top view thereof; and
FIG. 21 is a bottom view thereof.
